UNITED STATES PATENT OFFICE.

WARREN S. CREVELING, OF NEW YORK, N. Y., ASSIGNOR TO DANIEL T. MALLETT, OF SAME PLACE.

DESIGN FOR A LAMP-BODY.

SPECIFICATION forming part of Design No. 32,001, dated December 19, 1899.

Application filed August 30, 1899. Serial No. 729,011. Term of patent 34 years.

To all whom it may concern:

Be it known that I, WARREN S. CREVELING, a citizen of the United States, residing at New York, (Brooklyn,) in the county of Kings and State of New York, have invented and produced a new and original Design for Lamp-Bodies, of which the following is a full and complete specification, such as will enable those skilled in the art to which it appertains to make and use the same.

My invention relates to lamp-bodies, and is fully disclosed in the following specification, of which the accompanying drawings form a part, in which like reference characters denote like parts in the separate views, and in which—

Figure 1 is a front elevation of a lamp, showing my new design; and Fig. 2, a sectional view taken on the line 2 2 of Fig. 1.

Referring more particularly to the drawings, the leading and material feature of my design consists of a lamp-body formed to re-

present a bust A of a human figure provided with a base B of bulbous form. The head of the human figure represented by the bust A is provided with a hat D, in the form of an admiral's hat, and in which are formed a plurality of perforations E.

The lineaments of the features of the human figure represented by the bust A are configured to represent Admiral Dewey.

Having fully described my invention, I claim as new and desire to secure by Letters Patent—

The design for a lamp-body, substantially as shown and described.

In testimony that I claim the foregoing as my invention I have signed my name, in the presence of the subscribing witnesses, this 18th day of August, 1899.

WARREN S. CREVELIN
